ATTORNEY

UNITED STATES PATENT OFFICE.

PLINY W. SMITH, OF ROCHESTER, NEW YORK.

DEVELOPING TANK.

Application filed July 8, 1922. Serial No. 573,531.

To all whom it may concern:

Be it known that I, PLINY W. SMITH, a citizen of the United States of America, residing at Rochester, in the county of Monroe and State of New York, have invented certain new and useful Improvements in Developing Tanks, of which the following is a specification.

The object of this invention is to provide 10 a new and improved form of developing tank which is especially adapted for developing and fixing dental X-ray films. These tanks are made so that they will use a minimum amount of developing or fixing 15 solution and are intended to be partially immersed in a bath of water having a predetermined temperature.

Another object of this invention is to provide means whereby two of these tanks can 20 be connected together with one containing the developing solution and the other the fixing solution so that both of these tanks can be simultaneously rocked in the water bath, keeping the solution in both of the tanks in 25 constant motion.

These and other objects of this invention will be fully illustrated in the drawing, described in the specification and pointed out in the claims at the end thereof.

30 In the accompanying drawing:

Figure 1 is a perspective view of a pair of these tanks as they appear when connected together and placed in the water bath, the tank containing the water bath being 35 shown in section to better illustrate the supporting member mounting of the tanks containing the developing and fixing solution.

Figure 2 is a perspective view of a similar pair of tanks placed in the water bath 40 showing a modified form of connection between the tanks as well as modified support of the tanks in the water bath.

Figure 3 is a vertical sectional view of the tanks, the section being taken on the line 45 3^x-3^x of Figure 1.

Figure 4 is a detail sectional view of one of the clamps for fastening the tanks to the connecting member, the section being taken on the line 4^x-4^x of Figure 3.

50 Figure 5 is a detail sectional view of the connecting clip used in connection with the form of support illustrated in Figure 2, the section being taken on the line 5^x-5^x of Figure 2.

Figure 6 is a detail view of the clip with 55 which the tank is fastened to the rocking member.

In the several figures of the drawing like reference numerals indicate like parts.

In the developing of and fixing of dental 60 X-ray films a minimum amount of solution is used. For this reason the tanks in which these films are developed and fixed are made long and high and narrow. In order to get the best results it is necessary to keep the 65 developing and fixing solution at an even temperature and for this reason these long and high and narrow developing and fixing tanks are placed in a larger tank containing 70 a correspondingly larger volume of water. 75 The water in this tank serves to keep the developing and fixing solution at a corresponding temperature and by regulating the temperature of the water in the tank the temperature of the solutions in the smaller tanks is kept at the desired point.

In my present invention I have provided means whereby two of the tanks can be connected together and mounted on a single 80 rocking member so that the X-ray films can be developed in one of the tanks and then fixed in the other of the tanks while both of the tanks are simultaneously rocked in the water bath by the operator in order to keep the solutions therein in motion.

85 In the preferred form of mounting illustrated in Figure 1 each of the tanks 1 has a clip 2 fastened to the middle of the bottom thereof. For this purpose suitable lugs 3 may be provided on the sides of the tanks 90 between which the clip can straddle the tank as illustrated in Figures 1 and 3. The clips may be made so that they spring in place between the lugs and grip the tank so that with the aid of the lugs they will hold themselves 95 in place thereon. The clips may also be soldered or otherwise fastened to the tank in which case the lugs 3 may be omitted from the construction of the tank.

100 Each of the clips 2 is made up in the shape of a short and shallow channel in which the tank proper is adapted to rest. The bottom of the channel forming the clip has the pair of angular flanges 4 and 5 struck up thereon forming a triangular 105 socket into which is inserted the triangular rod 6. This rod is made long enough so that two of the clips 2 and their tanks can be

supported thereon. In this way two and if desired more of these tanks can be connected together and placed in a larger water tank. The connecting triangular rod 6 which connects the tanks 1 together gives the tanks stability and holds them in an upright position in the larger water tank 7. The rod 6 also serves as a rocker for the tanks so that when the tanks are connected together and placed in the water tank they can rock back and forth without danger of tipping them over in the water tank.

In use the tanks 1 are first connected together as above described after which they are placed into the larger water tank. The water tank contains cold water so that the temperature of the developing and fixing solutions in the tanks 1 is correspondingly lowered and kept at this temperature during the developing and fixing of the negatives. In this way the development and the fixing of the negatives is secured under the best conditions while the shape and size of the tank secures the development and fixing with the least amount of developing and fixing solution.

While developing and fixing negatives in the tanks 1 these tanks are rocked back and forth on the rod 6. The triangular edge of this rod on which the tanks are supported forms an ideal rocking bearing on which the tanks can be easily rocked. The triangular cross section of the rod and its engagement with the triangular socket formed on the clip 2 also serves to hold the two tanks parallel to each other without any other fastening means between them. While I have shown the rod 6 as triangular in cross section, it is understood that any other rod having an angular or rounded edge that can serve as a rocking bearing may be used instead.

In Figure 2 I have illustrated a modified form of the connection between a pair of the tanks 1 and the rocking member for supporting the same. In this form the two tanks are held together by means of a clip 10 which is slipped over the top edge of the two adjacent sides of the tanks to clamp them together and hold them parallel to each other. The tanks are supported in the water tank on a cradle 11 which is made up by two triangular frames that are connected together at the bottom by the cross bar 12. The cross bar 12 is adapted to support the tanks so that they can be rocked back and forth thereon in the same manner

in which the tanks are rocked on the rod 6.

I claim:

1. In a tank for developing and fixing 60 negatives, the combination of a large tank, a pair of smaller tanks mounted within said larger tank, a rocking member supporting said smaller tanks within said larger tanks and means for fastening said smaller tanks 65 to said rocking member to make them rock in unison with said rocking member.

2. In a tank for developing and fixing 70 negatives, the combination of a larger outer tank and a small inner tank mounted within said larger tank, a rocking member supporting said inner tank, fastening means carried by said inner tank to engage said rocking member to lock said rocking member to said inner tank.

3. In a tank for developing and fixing 75 negatives, the combination of a large outer tank and a small inner tank mounted within said larger tank, a socket member carried on the bottom of said inner tank, a rocking 80 member adapted to make engagement with said socket member and form a stationary rocking bearing on the bottom of said smaller tank.

4. In a tank for developing and fixing 85 negatives, the combination of a large outer tank and a pair of smaller tanks mounted within said larger tank, locking means for locking said pair of smaller tanks together and a rocking member mounted within said 90 larger tank to support said smaller tanks and allow said pair of tanks to rock in unison within said larger tank.

5. In a tank for developing and fixing 95 negatives, the combination of a large outer tank and a pair of small inner tanks, sockets formed on the bottom of each of said smaller tanks, a connecting member adapted to engage said sockets on said 100 smaller tanks and connect said tanks together, a rocking bearing formed on said connecting member on which said smaller tanks are adapted to rock within said larger tank.

6. In a tank for developing and fixing 105 negatives, the combination of a large outer tank and small inner tank, a clip attached to the bottom of said smaller tank, a socket member formed on said clip and a rocking member adapted to engage into said socket 110 member to form a rocking bearing for said smaller tank.

In testimony whereof I affix my signature.

PLINY W. SMITH.
